US0D1012742S

(12) **United States Design Patent** (10) Patent No.: **US D1,012,742 S**
(45) Date of Patent: ** Jan. 30, 2024

(54) **COLUMN DEPTH MEASURING GUIDE**

(71) Applicant: **AGILENT TECHNOLOGIES, INC.**,
Santa Clara, CA (US)

(72) Inventors: **Lucas Serge**, Wilmington, DE (US);
Wei J. Song, Vancouver, WA (US);
Eileen Huang, Hamburg (DE); **Olga Schikurski**, Karlsruhe (DE); **Kathleen Noblet**, Lafayette, CO (US)

(73) Assignee: **AGILENT TECHNOLOGIES, INC.**,
Santa Clara, CA (US)

(**) Term: **15 Years**

(21) Appl. No.: **29/840,063**

(22) Filed: **May 25, 2022**

(51) LOC (14) Cl. **10-04**

(52) U.S. Cl.

USPC **D10/70**

(57) **CLAIM**

The ornamental design for a column depth measuring guide, as shown and described.

DESCRIPTION

FIG. 1 is a perspective view of the column depth measuring guide;

FIG. 2 is a second perspective view thereof;

FIG. 3 is a rear plan view thereof;

FIG. 4 is a front plan view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines are included for the purpose of depicting portions of the column depth measuring guide that form no part of the claimed design.

1 Claim, 8 Drawing Sheets
